VOTING MACHINE

Alvin N. Gustavson, Jamestown, N. Y., assignor to
Automatic Voting Machine Corporation, a cor-
poration of Delaware

Application April 25, 1932. Serial No. 607,283

5 Claims. (Cl. 235—54)

This invention relates to an improvement in voting machines and more particularly to an arrangement for decreasing the resistance offered by certain indicators on the keyboard where there is a number of endorsed candidates.

In elections where certain candidates names appear in more than one place in a grouped office on the keyboard of a voting machine, provision must be made in the machine for preventing a voter from recording these candidates names more than once on any one ballot. Attachments for voting machines have heretofore been produced for the purpose of interlocking those straps which represent an endorsed candidate's name against each other but experience has shown that in order to prevent binding of certain endorsement interlocking straps, a sliding or floating interlock must be provided.

The preferred embodiment of this invention discloses a device in a voting machine which is adapted to prevent the voter from recording an endorsed candidate's name more than once on any one ballot and also to prevent certain interlocking straps from binding due to the lateral displacement of those interlocking straps which are voted by the indicators on the keyboard.

The principal object of the invention lies in the provision of a movable auxiliary interlock which will prevent binding of certain interlocking straps when the indicators connected therewith are moved to voting position.

Another object of the invention is to provide an endorsement interlock which will prevent the voter from recording an endorsed candidate's name more than once on any one ballot.

A further object of the invention lies in the provision of a removable endorsement interlock which may be easily attached to or removed from a voting machine as required.

Other and further objects of the invention will be apparent from a consideration of the following specification which is taken in conjunction with the accompanying drawings, and in which

Fig. 1 is a rear elevation of a voting machine showing the invention attached thereto with all of the interlocking straps in non-voting position;

Fig. 2 is a view similar to Figure 1, showing certain of the interlocking straps moved to voting position and the present invention moved longitudinally to a new position;

Fig. 3 is an enlarged vertical sectional view taken substantially on the line 3—3 of Figure 1;

Fig. 4 is an elevation of the device; and

Fig. 5 is an enlarged vertical sectional view, taken substantially on the line 5—5 of Figure 4.

Referring to the drawings and particularly to Figure 1, the invention, generally indicated by the reference numeral 10, is shown attached to one wall 11 of an interlocking channel 12. The device comprises a stationary back plate 13, the lower edge of which terminates in a right angle flange 14. A pair of reversely disposed channel portions 16, adjacent the extreme ends of the plate 13, are formed by a horizontal flange 17 and a vertical flange 18. Adjacent the upper edge of the plate 13 is a portion 19 which is bent slightly toward the wall 11 of the channel 12. Projecting horizontally and in the same direction as the flange 14, is a further flange 21 which is struck up from the central portion of the plate 13. Mounted on the plate 13 and projecting through co-axial openings 22 and 23 in flanges 14 and 21 respectively, is a member 24 which is provided at its lower end with a washer 26, permanently joined thereto. Interposed between the washer 26 and the lower side of the flange 14 is a compression spring 27. A cotter pin 28, located on the upper end of the member 24, locks said member to the plate 13.

Mounted on the face of the plate 13 and projecting in the direction of the flanges 14 and 21 is a pair of pins 29. Slidably mounted on the pins 29 is a plate 31 which is retained thereon by washers 32 and cotter pins 33. The plate 31 is provided with longitudinal slots 34 which permit sliding thereof relative to plate 13. The upper portion 35 of the plate 31 is slightly bent similar to the portion 19 of plate 13. Mounted on the upper side of portion 35, and extending generally in the direction of flanges 14 and 21, are rivets 36 which spacedly join a strip 37 to the plate 31. These rivets are equally spaced throughout the length of the strip 37 and plate 31. Interposed between adjacent rivets 36, and supported by means of a series of small slots 38 in the strip 37 and the portion 35, is a plurality of interlocking rollers 39. The rivets 36 and rollers 39 have substantially the same contour.

A rectangular cutout 41, in the central portion of the plate 31, provides the necessary clearance around the flange 21 so that the plate 31 may be freely moved from one extreme position to another.

Interlocking straps 42, interposed between adjacent rollers 43 in the interlocking channel 12, are provided with lugs 44 which are adapted to engage endorsement interlocking straps 46. Pivotally joined to the lower ends of these straps 46, by means of rivets 47 and interposed between

adjacent rollers 39, on the plate 31, are locking members 48.

The mechanism above described is concealed from view by a front panel 51. A bottom plate 52 is secured to the lower edge of the panel 51 by an angle bracket 53.

The endorsement interlock may be located in any desired position along the main interlocking channel 12 by compressing the spring 27 and placing the trough of the channel portion 16 into engagement with the under side of the wall 11. The spring 27, when released, causes the member 24 to bear against the bottom wall 52 of the machine, thus retaining the channel portion 16 of the plate 13 in pressure engagement with the underside of the wall 11. The endorsement interlocking straps 46 are connected to those candidate interlocking straps 42 which represent candidates endorsed by two or more political parties. In other words, if a candidate is endorsed by two parties, the two interlocking straps 42, which represent his name, are each provided with an endorsement interlocking strap 46. The interlocking members 48, which are connected to the straps 46, are interposed between a pair of adjacent rivets 36 and are separated from each other by one or more rollers 39 which lie therebetween. The endorsement interlocking straps 46 prevent a voter from moving both of the above mentioned straps 42 upwardly into voting position on the same ballot. Either one or the other of the straps 42 may be moved but not both. Since the interlocking feature herein disclosed is not novel and forms no part of this invention, other than to show its connection with the sliding plate on the endorsement interlock, further description thereof is unnecessary.

Figure 1 shows the normal position of the plate 31 before any of the interlocking straps 42 have been moved or voted. As soon as some of the interlocking straps 42 are drawn upwardly into voting position, as shown on the left side of Figure 2, the wedges formed on the bottom of said straps are also drawn upwardly so as to lie in a position between adjacent rollers 43. The upward movement of these wedges causes lateral displacement toward the right of all the rollers 43 and straps 42 which lie to the right of the moved or voted straps 42. If a number of straps 42 to the right of the elevation shown in Figure 1 are drawn upwardly, the rollers 43 and straps 42 lying to the left thereof will be moved in a similar manner. Since the interlocking straps 46 are attached to certain of the straps 42 and project downwardly between rollers 39 on the movable plate 31, it follows that the plate 31 will move to the right or left as certain of the straps 42 are moved into voting position. If the plate 31, which supports the endorsement interlocking rollers 39, did not move as the straps 42 move laterally, certain of the endorsement interlocking straps 46 would be inclined at such an angle as to bind between the rollers 39 and prevent the voter from moving them through an indicator on the keyboard. To prevent the straps 46 from binding, the plate 31 is adapted to slide from one position to another with the straps 42 and 46 so that the straps 46 are kept at all times in as near a vertical position as possible, thus leaving them free to move vertically.

Although applicant has shown and described but one modification of this invention, it is obvi-

ous to those skilled in the art that other modifications or adaptations may be made without departing from the spirit and scope of the invention as defined in the hereunto annexed claims.

Having thus set forth my invention what I claim as new and for which I desire protection by Letters Patent is:

1. In a voting machine having candidate interlocking straps which are displaced laterally when moved into and out of voting position, endorsement interlocking straps suspended from certain of said candidate straps, an endorsement interlock comprising a stationary plate and a movable plate, said endorsement straps being adapted to transmit lateral motion from said candidate straps to said movable plate whereby to prevent binding of said endorsement straps in said endorsement interlock. 80

2. In a voting machine having candidate straps means engaged with and causing lateral displacement of said straps during movement into voting position, endorsement interlocking straps suspended from certain of said candidate straps, and a removable endorsement interlock engaged with said endorsement straps, said interlock having a stationary and a movable plate, said movable plate being adapted to move laterally with said candidate straps to maintain a substantially vertical position of said endorsement straps at all times to prevent binding thereof in said interlock. 90

3. In a voting machine having candidate straps which are displaced laterally when moved into and out of voting position, endorsement interlocking straps suspended from certain of said candidate straps, an interlock engaged with said endorsement straps comprising a movable and stationary plate, said movable plate being adapted to move with said candidate straps whereby to prevent binding of said endorsement straps in said interlock. 100

4. In a voting machine having candidate straps, a candidate interlock for controlling the movement of said candidate straps, said candidate interlock causing lateral displacement of said candidate straps upon moving said candidate straps from non-voting to voting position, endorsement straps suspended from certain of said candidate straps, an endorsement interlock for controlling the movement of said endorsement straps, said endorsement interlock having a stationary and a movable plate, said movable plate being adapted to shift laterally with said candidate straps whereby to prevent binding of said endorsement straps in said endorsement interlock. 110

5. In a voting machine having candidate straps, a candidate interlock for controlling the movement of said candidate straps, said candidate interlock causing lateral displacement of said candidate straps upon moving said candidate straps from non-voting to voting position, endorsement straps suspended from certain of said candidate straps, an endorsement interlock for controlling the movement of said endorsement straps, said endorsement interlock having a stationary and a movable plate, said stationary plate being removably attached to said interlock, said movable plate being capable of shifting relatively to said stationary plate whereby to prevent binding of said endorsement straps in said endorsement interlock. 120

ALVIN N. GUSTAVSON.
